(57) **CLAIM**

The ornamental design for a firearm as shown and described.

DESCRIPTION

FIG. 1 is a left perspective view of the firearm showing our new design;
FIG. 2 is a right perspective view thereof;
FIG. 3 is a left side view thereof;
FIG. 4 is a right side view thereof;
FIG. 5 is a top view thereof;
FIG. 6 is a bottom view thereof;
FIG. 7 is a front view thereof;
FIG. 8 is a back view thereof;
FIG. 9 is a left perspective view of a second embodiment of the firearm;
FIG. 10 is a right perspective view thereof;
FIG. 11 is a left side view thereof;
FIG. 12 is a right side view thereof;
FIG. 13 is a top view thereof;
FIG. 14 is a bottom view thereof;
FIG. 15 is a front view thereof; and,
FIG. 16 is a back view thereof.

The broken lines illustrate portions of the firearm or environmental structure and form no part of the claimed design. The stipple shading depicts areas of the firearm having stipple texture but does not necessarily describe any particular stipple texture or color or material.
